Des. 234,371
Patented Feb. 18, 1975

234,371

MICROFILM RETRIEVAL TERMINAL OR THE LIKE

Richard J. Olson, Pittsford, N.Y.
(901 Elmgrove Road, Rochester, N.Y. 14650)

Filed July 13, 1973, Ser. No. 379,149

Term of patent 14 years

Int. Cl. D16—03

U.S. Cl. D61—1 N

FIG. 1

FIG.2

FIG.3

FIG. 1 is a left side and front perspective view of a microfilm retrieval terminal showing my new design;

FIG. 2 is a right side elevational view thereof; and

FIG. 3 is a rear elevational view thereof.

I claim:

The ornamental design for a microfilm retrieval terminal or the like, as shown.
